[57] ABSTRACT

A device for producing roll shaped packets of bags of plastic foil, whereby continuously a web is supplied in which the bags are held together through perforations, said device comprising two winding heads having lengthwise retractable and extendible winding fingers which can also be spreaded, the web during winding of one head running in between the fingers of the other head.

Both winding heads are mounted at diametrically opposed locations of a revolvable disc having two fixed positions.

The supply means comprise one roller within the line of circulations of the winding head situated at one side with respect to the vertical through the axis of the revolvable disc, and one roller outside the said line of circulation and situated at the opposite side of said vertical.

A switch mechanism under control of a bag unit counter sets the non-operative head into rotation and brings the operative head to a standstill, whereby a perforation is caused to break and the winding is taken over by the head just started.

DEVICE FOR PRODUCING ROLL-SHAPED PACKETS OF BAGS OF PLASTIC

This invention relates to improvements in a device for producing roll-shaped packets of bags of plastic foil, more specifically those whereby continuously a web is supplied in which the bags are held together through perforations.

A typical device of the type here involved is that which is disclosed in British Pat. Specification No. 1,332,544, this device comprising:

— two winding heads, each having a plurality of winding fingers which are lengthwise retractable and extendible between an operative position and a retracted position, and which can be moved towards each other between a spreaded position and an inner position for winding and for disengaging, respectively,

— the web supply guiding and the winding heads being arranged one with respect to the other such that during windings of one head the web runs in between the winding fingers of the other head,

— and the spacing between the heads being chosen such that there is at any moment at least one web perforation between them,

— further under control of a counter for the number of bag units supplied, a switch mechanism which sets the non-operative head into rotation and brings the operative head to a standstill,

— under the tensile stress thus produced in the web between the heads a perforation being caused to break and the winding being taken over by the head just started.

— after which the head brought to a standstill is drawn with its fingers out of the roll wound and subsequently, after a relative change of the web direction and the heads, the fingers of this head are extended again with the web running in between these fingers.

This prior device requires a rather large space. The device is intended to work up without interruption web material of such length that one may speak of a continuous process. In connection therewith it is desirable to have at least two winding heads, so that while a formed roll or packet is disengaged from one head the winding on the other head may go on. For transferring the supplied web from one head to the other the prior device makes use of a relatively big swinging arm which is provided at its extreme end with a second lever arm having a pair of reversing rolls. In connection with the big swing of this reversing lever a rather great deceleration in the take up speed of the foil web is created and such deceleration must necessarily be compensated for with an appropriate mechanism as is known in the art. Also the winding heads are mounted at fixed locations, so that the rolls produced have to be taken off at two locations in the machine. Finally in the prior device the winding is done at a relatively great diameter, having for consequence that the packet after disengaging it from the winding head has as a whole, a poor degree of stiffness. This appears particularly when the user has torn off several bags for his use; the remaining portion of the packet then often gets loose so that one can hardly speak anymore of a packet or roll that can be easily handled. In this respect it would be very advantageous to produce a roll wound on a small diameter, which would remain, when successively tearing off the bags for use, roll-shaped and of maximum stiffness up to the end.

Therefore the present invention aims to provide a device for the purpose mentioned which meets the aforementioned disadvantages and in which other advantages can be gained. More specifically the invention has for its object a compact, reliable, fast operating device for producing roll-shaped packets of bags having a high degree of stiffness.

In accordance with the present invention both winding heads are mounted at diametrically opposed locations of a revolvable disc having two fixed positions with respect to a fixed direction of supply of the foil web, the supply means comprising one roller within the line of circulation of the winding head situated at one side with respect to the vertical through the axis of the revolvable disc, and one roller outside the line of circulation of the winding heads situated at the opposite side of said vertical.

In this way it has become possible when one of the winding stations contains a sufficient length to simply put the other winding station into rotation, by which the web is caused to break of itself and the winding on the following head is initiated immediately. During such winding there will be a sufficient opportunity for the stations to change places by rotation of the disc, so that by the end of this displacement the first station, having delivered the packet wound, is prepared again to take over.

Preferably, according to the invention, each of the winding heads comprises no more than two winding fingers at short spacing. Apart from the fact that these two fingers have for result a very small effective winding diameter of the roll the advantage is obtained that when winding is taken over onto the new head, and with a substantially constant winding speed, the head will have obtained after one single revolution already a grip on the web sufficient to bring about breakage. Thus, at the beginning of the winding on a new station, it is not necessary anymore to initially apply a revolving velocity which is increased as compared with the normal winding velocity in order to obtain the desired good grip on the web.

In the accompanying drawings:

FIG. 1 schematically illustrates the principle of operation of the device according to this invention, thought of as an elevation of the revolvable disc of the device.

FIG. 2 shows an elevation partly in section of the complete device.

FIG. 3 is a side elevation according to the arrows III in FIG. 2.

FIG. 4 – 8 incl. illustrate details of the drive, viz. as elevations and in part sections respectively, as viewed in the direction of the arrows IV – VIII incl. of FIG. 3.

FIG. 9a is, in its left hand portion, a horizontal section through the axis of the revolving system of FIGS. 1 and 2, and in its right hand portion a plan view, the latter portion being shown in section and on an enlarged scale in FIG. 9b, the machine being shown in both FIG. 9a and 9b in a condition in which it has continued in its normal direction of movement 90° further than the condition shown in FIGS. 1 and 2.

FIG. 10 is an elevation according to the arrows X—X in FIG. 9a, and

FIG. 11 is a section according to the arrows XI—XI in FIG. 9b.

First a concise description will be given of the manner in which the winding takes place so that afterwards the function of the various parts in the further detailed

description will become more clear. FIG. 1 schematically represents the winding mechanism. A revolvable plate 1 supports at diametrically opposed locations two winding stations indicated as a whole by the reference numerals 2 and 2', respectively. The revolvable plate 1 is revolvable in the direction of the arrow P1 and each of the winding stations is revolvable with respect to the plate 1 in the direction P2 and P2', respectively. A guide roller for the foil is indicated at 4, said roller being rotatable with respect to the machine frame in the direction of the arrow P4. Said roller 4 is situated outside the area of the revolvable plate 1, i.e., at the left-hand side of the connecting line through the winding stations 2, 2' in the condition represented. A similar guide roller 5, also rotatable in the direction of the arrow P5 with respect to the machine frame, finds itself at the right hand side of the connecting line between the winding stations 2, 2'. Said roller 5 finds itself within the annular area in which the plate 1 rotates. Each of the winding stations comprises a pair of winding fingers 6, 7 and 6', 7', respectively.

In the condition represented in FIG. 1 the winding takes place. The foil material is supplied from the top and runs over the guide roller which rotates at a circumferential velocity equal to the supply velocity of the foil, between the stationary winding fingers 6, 7 of the upper winding station 2. In the standstill condition of this station the line connecting the winding fingers 6 and 7 is inclined under about 45° with respect to the diameter going through the stations 2, 2'. With the arrangement of the guide rollers 4 and 5 as represented the direction of movement of the foil 8 therefore extends under about right angles to the line interconnecting the winding fingers 6 and 7. Thereupon the foil is led around the guide roller 5 and subsequently runs further downwardly where the foil material is wound about the fast rotating winding fingers 6', 7' of the station 2' into a roll 9.

When the roll 9 contains a sufficient wound length the winding fingers 6, 7 of station 2 are caused to rotate at high speed. Thereby the foil material which finds itself between station 2 and station 2' is drawn taut over the roller 5 causing breakage of the foil web to occur at the location of the perforation present. While in this way, during speedy rotation of station 2, the winding of the succeeding roll is initiated, station 2' continues to rotate at low speed in order to wind the last part of the foil. After several revolutions the fingers 6' and 7' are retracted and the produced roll 9 is taken off. Thereupon, the winding at station 2 being continued, the revolvable plate 1 is rotated slowly until the operative station 2 will have reached the location of station 2' at the bottom. Thereby the foil material is guided of itself again until it passes over roller 5 just like in the condition represented. When station 2' will have reached again the location of station 2, the fingers 6', 7' will be extended on either side of the foil web 8, which meanwhile proceeds, and therewith station 2' is ready to take over again in the manner described.

FIG. 2 shows an overall view of the whole winding device with the drive in form of a side elevation, partly in section. Top right in this figure the revolvable plate 1 with the pair of winding stations 2, 2' is visible as closure of a housing, as a whole referenced by 10, containing the greater part of the mechanism for retracting or extending, respectively, the winding fingers 6, 7 and 6', 7', respectively.

In the left hand portion of the drawing the various drives are represented comprising, opposite the revolvable plate 1 with the winding stations 2, 2', a similar revolvable plate 11 with a pair of driving heads 12, 12'. The housing containing the drives is referenced as a whole by 13.

In the detailed description of the drive which is given below reference is also made to FIG. 3, representing a section according to the arrows III—III in FIG. 2.

On the bottom of the housing two electric motors are visible. Motor 14 is a high speed motor with the function of driving the winding heads. Motor 15 is a low speed motor having the function of intermittently causing a rotation over 180° of the revolvable disc which supports the winding stations, and also of slowly driving each of the winding stations during the last revolutions after breakage of the foil web.

The high speed motor 14 has its shaft 16 provided with a pulley 17. Over the latter an endless belt 18 extends. This belt 18 further extends over a pulley 19 which constitutes part of a coupling mechanism which will be described in detail and which is referenced as a whole by 20 (represented separately in FIG. 4). Further the belt 18 extends over a pulley 21, which also constitutes part of a similar coupling mechanism referenced as a whole by 22 (represented separately in FIG. 5).

As will be described in more detail it is in this way possible to transmit the high drive velocity through belt pulley 23 of coupling mechanism 20 upwardly by means of belt 24, and in similar manner with pulley 25 in the coupling mechanism 22 the high drive speed on belt 26 can be transmitted upwardly. Belts 24 and 26 ultimately drive the drive heads of the winding stations.

The low speed motor 15 has its shaft 27 provided with two belt pulleys 28, 29. Over pulley 28 a belt 30 extends which goes further over a pulley 31 constituting again part of a coupling mechanism referenced as a whole by 32 (represented separately in FIG. 6). In this way as will be explained in detail the low drive speed can, by means of pulley 33 in coupling mechanism 32 as well as through belt 34, be transmitted upwardly for slowly revolving the revolvable plate which supports the winding stations.

The other pulley 29 of the low speed motor 15 drives a belt 35 extending over pulley 36 of the coupling mechanism 20 as well as over pulley 37 of the coupling mechanism 22. In this way either of the coupling mechanisms 20, 22 has supplied on a pulley the low drive speed being transmittable upwardly through pulley 23 with belt 24 and pulley 25 with belt 26, respectively, for driving the winding heads at low velocity during such time period as is necessary.

For belt 18 a tension roller 38 is provided, supported by a lever 40 pivotable about a shaft 39. In similar manner belt 35 is tensioned by the tension roller 41 supported by the lever 42 which is pivotable about the shaft 43.

Now the various coupling mechanisms mentioned already will be described, with which the upwardly extending belts can be given desired speeds at desired moments.

In FIG. 4 to the right of the coupling casing 44 pulley 36 is visible which is driven from the low speed motor through belt 35. The coupling casing 44 itself, which has an electric control, has not been represented in detail because one may use for this any known structure

commercially available which is adapted for coupling two shafts having coinciding axes. To the left of the coupling casing 44 one finds first pulley 19 driven from the high speed motor 14 through belt 18. Then pulley 23 is driven, over which belt 24 extends which transmits the drive speed upwardly. Either of pulleys 19 and 23 is fixedly attached to the shaft end at the left hand side of the coupling casing 44. When the coupling is disengaged it is thus possible to transmit the speed of the high speed motor through pulley 28 to pulley 23, irrespective of whether pulley 36, which is driven by the low speed motor 15, is or is not actually driven. When coupling 4 is engaged the lower drive speed of pulley 36 is transmitted to pulley 23, pulley 19 running along idle.

FIG. 5 shows the coupling mechanism 22 which for the greater part corresponds with the one of FIG. 4. On the shaft end to the right of the coupling casing 44 one finds pulley 37 which is driven from low speed motor 15 through belt 35. To the left of the coupling casing first pulley 21 is provided, driven from high speed motor 14 through belt 18, and subsequently pulley 25 through which belt 26 transmits the drive upwardly. Either of pulleys 21 and 25 is again fixedly attached to the shaft end. The operation is analogous to what was described with reference to FIG. 4. The only structural difference between FIG. 4 and FIG. 5 is that in FIG. 4 the hub 46 of pulley 23 projects to the right with respect to the pulley at the same side an intermediate piece 47 being placed on the shaft, so that in the end pulley 23 has a certain spacing with respect to pulley 19. In FIG. 5 pulley 25 has been placed on the shaft in the reverse condition, i.e., with the extended portion 46' of the hub to the left, beside it the intermediate piece 47' being provided, so that pulley 25 is lying more close to pulley 21. In this way the mechanisms 20 and 22 can be arranged symmetrically in the drive housing, the belts extending one in front of the other.

FIG. 6 shows an axial section through the coupling mechanism 32. To the right of the coupling 48 proper a pulley 31 is placed on the shaft, said pulley being driven from the low speed motor 15 through belt 30. To the left of the coupling in this case only pulley 33 is provided, over which belt 34 transmits the driving motion upwardly. The coupling 48 proper in this case is of a type which also contains a braking device for the driven side, in this case the left hand side. Its function will be explained later on.

The manner in which the drive speeds of the belts 24, 26 and 34 are worked up in the top of the housing 10 now appears from FIG. 7. The revolving disc 11 is affixed to a shaft 51. This shaft is at 52 rotatably bearing in the housing wall 13. On shaft 51 first, to the left in FIG. 7, a belt pulley 53 is visible which is fixedly mounted on spindle 51 by means of a clamping socket 54. Belt 34 at any time brings along upwardly a low drive speed with which, through the fixed connection between pulley 53 and shaft 51 and subsequently the fixed connection between shaft 51 and disc 11, this disc can be given a slow rotation.

On shaft 51 further a bushing 55 is provided. At either end thereof pulleys 56 and 57 are fixedly attached by means of keyings 58 and 59 respectively. For the rest pulleys 56 and 57 are, by means of a set of bearing 60 and 61, respectively, rotatable with respect to shaft 51. Pulley 56 receives belt 24 coming from below and which, in the manner described, a high as well as a low

drive speed can be given as desired, and it is this drive which is then transmitted immediately to pulley 57, independent of shaft 51. Over pulley 57 drive belt 62 extends (vide FIGS. 2 and 3) to one of the heads.

On the aforementioned bush 55 a pair of bearings 63 and 64, respectively, is provided for support of a pair of pulleys 65 and 66 which are interconnected for example by means of threaded bolts such as 67. Pulley 65 receives belt 26 driven from below, which can be driven at high or low speed as desired, so that this speed can be transmitted through pulley 66 to belt 68 (vide again FIGS. 2 and 3) for driving the other head. Because of the arrangement with the bearings 63 and 64 this transmission with the pulleys 65 and 66 is independent of bush 55 and pulleys 56 and 57 belonging thereto, as well as of shaft 51.

Each of the aforementioned belts 62 and 68 extends over an idle roller 69 and 70, respectively. These rollers have identical structures. Roller 70 is represented separately again in FIG. 8. In the latter figure it is visible that disc 11 bears a short support 71, attached by means of a bolt 72 threaded through an aperture 73 in the disc into a threaded bore 74 of support 71. The other end 75 of support 71 supports a bearing 76 for pulley 70. As a matter of course the structures of guide rollers 69 and 70 are different in the length of their supports such as 71, such that this length is adapted to the spacing between pulleys 57 and 66, respectively, over which the concerned belts extend, and plate 11.

Thus belt 62 extends over guide pulley 69 and over pulley 77 where the head 12 (FIG. 2) is driven. In symmetrical manner belt 68 extends over guide pulley 70 and drive pulley 78 for the other drive head 12' (vide FIG. 2).

From the structure as described above it will be apparent that the running of the pair of drive belts 62 and 68, so the rotation of the drive heads 12 and 12', can take place independent of the drive which now and then rotates the revolvable plate 11 as a whole; the two drives don't hinder each other in whatever way.

The details of the upper drive head 12 are to be found in FIG. 9a. In a bore 81 of disc 11 a cylindrical bush 82, having a flange 83 is provided. Flange 83 is sunk at the back of disc 11. The bush with flange is affixed with respect to disc 11 by means of bolts such as 84. In the cylindrical aperture 85 of bush 82 a shaft 86 is provided rotatably supported by means of three bearings 87, 88, 89. At the right end the shaft 86 supports a disc 90 on which a drive head 91 is fastened, for example by means of a pair of bolts such as 92. This head 91 is, in a manner still to be described, adapted to impart rotation to the winding fingers.

At the other side of the revolvable disc 11 an electromagnetic brake 92, 93 is provided. This brake may be of any known, commercially available type, so that details need not be described. The part 92 of the brake is, by means of a flange 94 and bolts such as 95, fixedly attached with respect to the flange 83 of the cylindrical bush 82, so fixed with respect to the disc 11. The rotating brake portion 93 is fixedly mounted onto the shaft 86. The shaft 86 also supports the already mentioned pulley 77, the whole being completed by the provision of a vane 96 for the proximity switch which will be described later on. This vane 96 may also be of a known structure. Vane 96 may be fastened with bolts such as 97 against the outer face of pulley 77.

It is thus visible that the belt 62 extending over the pulley 77 may set the drive head 91 for the winding fingers into rotation.

In FIG. 1 it was shown already that the winding fingers such as 6, 7 in each of the winding stations should be brought to a standstill in a fixed condition, viz. under about 45° with respect to the line interconnecting the two winding stations in the device. For only in this way it is ensured that, while a station in the lowermost position such as 2' in FIG. 1 is in operation, the fingers 6, 7 of the upper station 2 can be extended on either side of the proceeding foil web 8, in order that the winding may be taken over. It is with a view to this function that the drive head represented in FIG. 9a is provided with a brake 92, 93. With the aid of vane 96 and an associated proximity switch the brake is energized at the desired moment, so that head 91 will come to a standstill in the desired condition. The proximity switch itself has not been represented in the drawing. The details of it, as well as of the electrical circuitry with the control of the magnetic brake will not need any further description for the man skilled in the art.

In FIG. 9a it is further visible that the extremities of the winding fingers 6, 7 directed towards the drive head 91 and which are made substantially cylindrical, are provided with bevelled faces 101. These bevelled faces are provided at the side of each finger directed towards the other finger, so directed towards the axis 102 of the drive head 91 or the rotating winding station as a whole, respectively. The drive head 91 is provided with a pair of cavities such as 103, the shape of which corresponds with the extremity of the drive finger, i.e., each of these cavities is substantially cylindrical, such as at 104, but having an inclined face 105 at the side directed towards the axis 102 of the cavity 103. The functions of the bevelled face 101 and the abutting face 105 for each of the fingers is that the fingers can be given two different mutual spacings: the fingers are extended from right to left in FIG. 9a with a small spacing, and when the bevelled face 101 abuts against the inclined face 105 each of the fingers will be forced outwardly over a small distance into the position represented in FIG. 9a. For the right hand extremities of fingers 6 and 7 a similar provision has been made which will be described later.

To the right in FIG. 9a and in FIG. 9b a partial representation is given of the revolvable plate 1 with the details of the winding head 2' cooperating with the drive head 12' described. The mechanism for retracting the extending again the winding fingers 6, 7 comprises a housing 106, for the greater part circularly symmetric, having an axis which coincides with the already mentioned axis 102 of the drive head at the left. This housing 106 is as a whole movable over a certain distance along the aforementioned axis. For this purpose the housing has at the rear a plate 107. This plate is provided with a bore in which a pipe or bush 108 is mounted, such that the axis thereof extends parallel to the axis 102. This bush 108 preferably has a great length as compared with its diameter. On either end in the interior of the bush 108 a ball bearing such as 109 is provided, with the aid of which the bush is movable in axial direction with respect to a guide pin 110, the end of which may be fastened to plate 1 by means of a simple screw connection 111 at the end.

In plate 107 a second bore 112 is provided for the end of a piston rod 113 which constitutes part of a

pneumatic cylinder 114 (vide also FIG. 2). This pneumatic cylinder 114 can be lodged at short distance from the axis 102 in the space between the revolvable plate 1 of the right hand machine portion 10 and the revolvable plate 11 of the left hand machine portion 13. By means of this cylinder/piston rod combination 114, 113 the housing 106 with the fingers 6', 7' is moved to the left and to the right at desired moments. In FIGS. 9a and 9b the housing 106 with the fingers 6' and 7' has been represented in the extreme left position, in which the winding fingers are extended into the space between the revolvable plates 1 and 11, so ready for winding, in FIG. 2 the housing 106 being represented in the extreme right position in which the fingers 6' and 7' have been retracted.

Again referring to FIG. 9b it is visible that inside the housing 106 a bushing 115 is provided. This bushing 115 again has its axis coinciding with the axis 102 and is rotatable about this axis inside the housing 106. For this purpose the bushing 115 is supported inside the housing 106 by means of three ball bearings 116, 117, 118. In order to be able to enclose the bearing 117 the housing 106 comprises a separate annular part 119, the next bearing 118 being enclosed by means of the closing disc 120. The entirety can be kept together for example by means of bolts 121. The bearing 116 is enclosed by disc 122. The latter can be sunk into the back of the revolvable disc 1. At the front of disc 1, at the left side of FIG. 9b, a double ring 123, 124 is provided. In this double ring by means of a bearing 125 a set of plates 126, 127 is rotatable. Making double rings 123, 124 and plates 126, 127 is done as will be understood in order to be able to enclose the bearing 125. The two rings 123 and 124 together are fastened to the revolvable disc 1 by means of bolts such as 128, bolts such as 129 fastening the two rotatable plates 126, 127 one to the other. The front plate 127 is provided with a pair of round apertures 130, 131 serving to let the fingers 6' and 7', respectively, pass through. The rear plate may have one single big round aperture 132. The apertures 130, 131 have greater dimensions than the diameter of the cylindrical part of the winding fingers 6', 7' as far as is necessary in order to enable the lateral movement of these fingers (vide also FIG. 10).

The extreme ends of the two fingers 6', 7' lying to the right of the double plate 126, 127 are provided with a substantially square cross sectional area (vide FIG. 11). These portions of the fingers are referenced 136', 137'. These square finger heads are located in square holes 138 and 139 respectively, in the bushing 115. In horizontal direction in FIG. 11 (so in the direction at right angles to the plane of the drawing in FIG. 9b) the square finger heads 136', 137' are simply slidable with a very small clearance inside the cross sectional dimensions of the square hole 138 or 139, respectively. In the vertical direction in FIG. 11 (so the vertical direction in the plane of drawing in FIG. 9b) the square holes 138, 139 are to a sufficient degree bigger than the dimension of the square finger heads 136', 137' in the same direction in order to allow for the desired displacement of fingers 6', 7' in lateral direction one with respect to the other.

At the location where the cross sectional view of FIG. 11 was taken each of the square finger heads 136', 137' is provided at opposite locations with a pair of block shaped members 140-143 incl. These members are fixedly attached to the square finger heads, but under

a certain inclination of their axes with respect to the finger axis as represented. Each of these small blocks is guided in a corresponding inclined slot of rectangular cross sectional area 144-¹⁴⁷ incl.

At the location where each of the inclined slots reaches the inner wall of bushing 115 there is also provided a bore 148, at right angles to the bushing axis, in which a compression spring 149 is located which urges a plug 150 against the extreme edge of the small block concerned.

Near the rear end of the square heads 136', 137' an entirely similar set of small blocks is provided onto the finger heads, with corresponding inclined slots in the bushing 115, as indicated by 151.

Laterally through the two square finger heads 136', 137' a pin 152 is put through corresponding borings. This pin 152 has a clearance in the bore holes of the finger heads such that lateral displacement of the finger heads with respect to each other is permitted, but it ensures that they do move together in axial direction.

In the absence of other forces the eight guide blocks will be urged, under the influence of the springs such as 149, obliquely away in the direction of the axis 102, with the result that the fingers will take up a position in which their mutual distance has the smallest value. When, by operation of the pressure cylinder 113, 114, the housing 106 with the fingers is displaced to the left at the extreme ends of the fingers 6', 7' with their bevelled faces such as 101 abut against the drive head such as 91 at the opposite side, the fingers 6', 7' will experience a force directed to the right. The inclined blocks in the inclined slots of bushing 115 then allow for a small relative displacement of fingers 6', 7' to the right, whereby simultaneously the fingers will move somewhat away from each other into the position represented in FIG. 9a and FIG. 9b. When thereupon a foil bundle is wrapped around fingers 6', 7', and the winding is ended, pressure is admitted again in the pressure cylinder 114 having for effect that the housing 106 starts to move to the right in FIG. 9a and 9b. Thereto the foil roll wound onto the fingers will ensure a sufficient resistance in order that a minor relative displacement of the small blocks in the inclined slot in bushing 115 will take place, by which the fingers will move towards each other again. Thereby the roll of foil is disengaged. As the supply of pressure medium to the pneumatic cylinder 114 proceeds the housing 106 together with the winding fingers 6', 7' will move to the right, the fingers will be fully retracted and the produced roll of foil material will become free to be taken away.

At the rear of the housing 106 described above, just like at the rear of the drive head 12, 12', an electromagnetic brake 157, 158, is provided. The one brake portion 157 is attached to the end plate 120 of housing 106, for example by bolts such as 153. The other brake portion 158 is arranged on a hub 154 which is, by means of a flange 155 and screws such as 156, connected with the rear end of bush 115. This brake 157, 158 is energized simultaneously with brake 92, 93 at the drive side.

The other winding head 2 is fully identical to the described winding head 2'.

FIG. 2 shows that the right hand end of the guide rod 110, along which the housing 106 is movable under the influence of the pneumatic cylinder, is mounted in a revolvable disc 161. It will be understood that the other housing is mounted in similar manner. The disc again

has its axis coinciding with axis 102. The disc is rotatably mounted in the right hand machine wall 162, as indicated by 163, inside this mounting a rotatable coupling 164 being provided for the supply of pneumatic medium to the air cylinders such as 114.

What I claim is:

1. A device for producing roll-shaped packets of bags of plastic foil from a continuously supplied web in which the bags are held together through perforations, 10 said device comprising:

two winding heads, each having a plurality of winding fingers which are lengthwise retractable and extendible between an operative position and a retracted position, and which can be moved towards each other between a spreaded position and an inner position for winding and for disengaging, respectively,

the web supply guiding and the winding heads being arranged one with respect to the other such that during winding of one head the web runs in between the winding fingers of the other head, the spacing between said heads being such that there is at any moment at least one web perforation between them,

a counter for indicating the number of bag units supplied and a switch mechanism responsive to said counter to set the non-operative head into rotation and to bring the operative head to a standstill to increase the tension on said web between the heads whereby under the tensile stress thus produced a perforation is caused to break and the winding of the web is taken over by the head just started into rotation.

said switch mechanism further retracting the fingers of the standstill head out of the wound roll and subsequently, after a relative change of the web direction and the heads, extending again the fingers of this head with the web running in between these fingers,

both said winding heads are mounted at diametrically opposed locations of a revolvable disc to define two fixed positions with respect to a fixed direction of supply of the foil web,

supply means for said web comprising a first roller within the line of circulation of the winding head situated at one side with respect to the vertical through the axis of the revolvable disc, and a second roller outside the line of circulation of the winding heads situated at the opposite side of said vertical.

2. A device as defined in claim 1, wherein each of the winding heads comprises no more than two winding fingers at short spacing.

3. A device as defined in claim 1, wherein opposite the winding heads a pair of drive heads for the rotary movement of the winding heads is provided, with which the fingers of each of the winding heads in their extended conditions cooperate, said drive heads also being mounted on a revolvable disc which ensures the rotation of the disc supporting the winding heads.

4. A device as defined in claim 3, wherein in each of the winding stations the displacement of the winding fingers from the condition in which the fingers lie close to each other to the spreaded condition and vice versa is obtained by providing each of the fingers with guide members arranged under an appropriate small angle relative to the finger axis, said members cooperating

with guide faces arranged under a corresponding angle in a bushing which supports the fingers.

5. A device as defined in claim 2, wherein the fingers are arranged inside a housing which is movable in the direction parallel to the finger axis.

6. A device as defined in claim 5, wherein the displacement of the housing occurs by pneumatic means.

7. A device as defined in claim 1, wherein the drive comprises at least one high speed motor for the winding heads and a motor for the revolvable disc.

8. A device as defined in claim 7, wherein the motor for driving the revolvable disc is a motor running at relatively low speed, and transmission means to said revolvable disc for additionally driving the drive heads at the winding stations by said motor.

9. A device as defined in claim 8, wherein a belt drive is provided comprising, in coaxial arrangement with the axis of the revolvable disc which supports the drive heads, the following pulleys: one pulley which is

adapted to be driven from the high speed motor by intermediary of a coupling and having a fixed connection with a pulley by which the rotation is directly transmitted to one of the drive heads, one pulley independent of the former but also adapted to be driven by the same high speed motor and which has a fixed connection with a second pulley for driving the second drive head, and finally a pulley adapted to be driven from the other motor and having a fixed connection with the revolvable disc which supports the drive heads.

10. A device as defined in claim 9, wherein the coupling mechanism connecting the high speed motor with the two pulleys for the drive heads also comprise pulleys adapted to be driven from the other motor.

15 11. A device as defined in claim 1, wherein each of the winding heads is provided with means adapted to bring the rotary motion to a standstill with a definite condition of the fingers.
